CLAIM

The ornamental design for an end plate for a filter element, as shown and described.

DESCRIPTION

FIG. 1 is a top perspective view an end plate for a filter element;

FIG. 2 is a bottom perspective view of an end plate for a filter element;

FIG. 3 is a front view of an end plate for a filter element;

FIG. 4 is a back view of an end plate for a filter element;

FIG. 5 is a top view of an end plate for a filter element;

FIG. 6 is a bottom view of an end plate for a filter element;

FIG. 7 is a left-side view of an end plate for a filter element; and,

FIG. 8 is a right-side view of an end plate for a filter element.

The broken lines in the drawings depict portions of the end plate for a filter element and form no part of the claimed design.
